UNITED STATES PATENT OFFICE.

ROBERT DILIVAN PARKS, OF LOHRVILLE, IOWA, ASSIGNOR TO SIGFRED ADOLPH NYSTEDT, OF STORM LAKE, IOWA.

PAPER CUTTING AND VENDING MACHINE.

Application filed October 29, 1925. Serial No. 65,584.

This invention relates to a coin-controlled device for dispensing sanitary toilet napkins, and especially adapted to be installed in public toilets, so that a person using the 5 same may be protected against possible infection from anyone who has preceded him.

The general object of the invention is to provide improved apparatus of this character, which is efficient in its operation, and 10 which, when operated by the use of a coin, may be operated to deliver a sheet of paper cut in the desired manner to be used for covering the seat. The sheet when delivered is flat and unfolded, ready for immediate 15 use. The knives are serrated, and so arranged that they are projected into slots in a base plate. They do not depend on a shearing edge, or a close fit to cut the paper which is used, and they do not require sharpening. When a napkin is cut from the 20 remainder of the roll, a horse-shoe shaped cut is made at the same time in the succeeding napkin.

The specific construction of the invention, 25 and the advantages resulting therefrom, will be more fully explained in the following detailed description taken in connection with the accompanying drawings, which illustrate one embodiment thereof.

30 In the drawings:

Figure 1 is a side elevation of the invention with the casing and the supporting base shown in section.

Figure 2 is a vertical transverse section 35 taken substantially on the line 2—2 of Figure 1.

Figure 3 is a rear elevation of the device removed from its support.

Figure 4 is a vertical longitudinal section. 40

Figure 5 is a section taken substantially on the line 5—5 of Figure 1.

Figure 6 is a section taken substantially on the line 6—6 of Figure 1.

Referring in detail to the drawings, the 45 invention comprises a base plate 10, secured in spaced relation to a support 11, by means of suitable brackets or angle bars 12. The base 10 and the mechanism supported thereby are enclosed by a casing 13, which may be secured in any suitable manner. Mounted in suitable bearing plates 14, in front of the base 10, is a shaft 15 adapted to support a roll of paper 16, of suitable quality and the desired width. A paper guide plate 17 is 50 mounted in front of the base 10, and a strip 55

of paper 16^a, as it is unwound from the roll 16, passes over a roller 18 at the upper end of the guide plate 17, downwardly behind the latter, and through a slot 19 in the bottom of the casing 13. 60

A shaft 20 is mounted in bearing plates 21 secured to the base 10 near the bottom thereof, and secured to this shaft are a pair of feed rollers 22, the upper guide plate 17 being cut away, as at 23, to permit these 65 rollers to come in contact with the strip of paper 16^a. One end of the shaft 20 projects through the casing 13, and is there provided with a crank 24, by means of which it may be rotated. Cooperating with the rollers 22 are pressure rollers 25 of felt, cork or the like. Each of these pressure rollers is made in two sections secured to a shaft 26, which is mounted in the slotted brackets 27, which are secured to the base 10. The 70 base is cut away, as at 28, to receive the roller, and a flat spring 29 is secured at one end by a clip 30 to the rear side of the base, and provided at its free end with a curved portion 31 bearing against the shaft 26 between 75 the two roller sections to hold the latter yieldingly in contact with the paper strip 16^a. It will be understood, therefore, that the feed roller 22, when released, may be rotated by means of the crank 24 to feed the 80 strip of paper downwardly through the slot 19. 85

When a sufficient length of paper has been fed to form a napkin, the latter is severed from the remainder of the strip by means 90 of a horizontal serrated knife 32, which is adapted to be projected across the strip of paper into a recess 33, formed in the base 10 for receiving the same. At the same time, a horse-shoe shaped cutter 34, also having a serrated edge, is projected across the strip of paper into a similarly shaped slot 35 formed in the base 10. The cutter 34 is secured to a knife plate 36, and brackets 37 secured to the latter support the horizontal 95 cutter 32. The brackets 37 have portions cut away, as at 38, so that the shaft 20 will not interfere with the movement of the knives. The brackets 37 are secured to the bar 39, and said bar 39 and the knife plate 36 are slidably mounted on guide pins 40, which extend forwardly from the base 10. 100

The mechanism for actuating the cutters includes a shaft 41, extending from end to end of the bar 39, and having a toggle plate 105

42 secured to each end thereof. The extremity of the toggle plate 42 is pivotally connected at 43 to the end of a cooperating link 44, the other end of which is pivotally mounted at 45 on the side of the base 10. The toggle plate 42, at one end of the shaft 41, is provided with a shoulder 46 adapted to be engaged by an actuating lever 47, which is mounted on the shaft 41, and projects forwardly through a slot 48 in the casing 13. A locking pin 49 is mounted on one of the pivots 43, and extends downwardly through a slotted guide bracket 50 secured to the adjacent plate 21, and the extremity of the pin 49 normally projects into a hole 51 in a drum 52, which is secured to the shaft 20, thereby locking the latter and the feed rollers 22 carried thereby.

When the lever 47 is moved downwardly 20 toward the dotted line position shown in Figure 1, the toggle plate 42 is rocked with the shaft 41, spreading the toggle formed by the plate 42 and link 44, thereby moving the bar 39 toward the dotted line position. 25 This movement also lifts the locking pin 49, and when the lever 47 has reached the lower end of the slot 48, the pin 49 is completely withdrawn from the drum 52, so that the shaft 20 is free to rotate. As soon as the 30 pin 49 is free from the drum 52, it is carried to the inner end of the slot in the bracket 50 by a coil spring 53, which bears against the head of the pin. When the bar 39 is moved forwardly to the position indicated 35 by dotted lines in Figures 1 and 4, the knife plate 36 and the knives 32 and 34 are also moved forwardly to release the paper. This compresses the coil springs 54, which surround the guide pins 40 between the stops 40 55 and the rear faces of the knife plates. The knives, however, are at this time prevented from returning to the slots in the base 10 by the pin 49, the lower end of which engages the surface of the drum 52. The 45 surface of the latter is formed with a helical groove 56 in which the end of the pin 49 rides, and as the shaft 20 is rotated to feed down the paper, the pin rides along the groove 56 until it reaches the hole 51 and drops into it. At this moment, the springs 54 return the knife 32 into the base 10, cutting off a napkin, so that it may be easily withdrawn, and the knife 34 cuts the horse-shoe shaped slit in the succeeding napkin. 50 The groove 56 may be of any desired length, but three turns will ordinarily be sufficient to feed down the required amount of paper.

The mechanism above described for feeding down the paper is particularly adapted 60 to be used with coin-controlled mechanism, as indicated in Figure 1. To this end, a trip member 57 is pivotally connected to the lever 47, and the free end of the member 57 is connected by a coil spring 58 to a fixed member 65 59. The trip member 57 is formed with a

hook 60 adapted to ride against a fixed abutment 61 as the lever 41 is depressed. Normally, in the absence of a coin, the hook 60, as the lever 47 moves downwardly, will engage a notch 62 formed in a fixed member 70 63, and will positively stop the movement of the lever 47 before it has moved far enough to release the locking pin 49 from the drum 52. When, however, a coin is dropped into the slot, it will roll downwardly by an irregular path, as indicated by the several dotted line positions shown in Figure 1, until it lodges against the shank of the trip member 57 underneath the hook 60. If a coin of the proper size is used, it will force the trip member 57 rearwardly, so that it will clear the end of the member 63, and permit the lever 47 to be moved to the bottom of the slot 48, and to release the dispensing mechanism. The coin-control mechanism may, of course, be adjusted so as to use coins of any size desired.

In the operation of the mechanism above described, the insertion of the coin permits the lever 47 to be moved to the bottom of the slot 48, as indicated in dotted lines in Figure 1. This spreads the toggle formed by the plate 42 and link 44 until the bar 39 reaches the position shown in dotted lines, and the cutters 32 and 34 are drawn forwardly out of the path of the paper. The spreading of the toggle also withdraws the locking pin 49, and the latter is immediately moved by the spring 53 toward the inner end of the drum 52, thus releasing the feed rollers, and also compelling the knives to remain in their forward position until the feed rollers have been turned through three complete revolutions. The cutters are then projected again into the respective slots 33 100 and 35 by the action of the springs 54, the toggle and the bar 39 being at the same time restored to their original positions. Thus, the napkin, which is dispensed from this machine, is delivered flat and unfolded, and 105 is ready for immediate use without any further unfolding or tearing or forming. The serrated cutters are so arranged that they drop into the slots in the base, and do not depend on a shearing edge or a close fit to cut the paper which is used. The outer casing may be readily removed by a person authorized to do so for the purpose of replenishing the supply of paper or inspecting the machine. The napkins are made from absorbent paper, such as is ordinarily used for 110 toilet paper, and will readily pass through the plumbing. The napkins will completely protect the user from any infectious disease.

While I have shown and described in detail one specific embodiment of the invention, it is obvious that many modifications may be made therein without any material departure from the salient features of the invention as expressed in the claims.

What is claimed is:

1. In a device of the character described, the combination of hand crank operated means for feeding a strip of paper, a cutter guided for rectilinear movement across the path of said strip, means for positively locking the feeding means and at the same time projecting the cutter across the strip, and hand lever operated means for retracting the cutter and for releasing the feeding means only when said cutter is fully retracted. 5
2. In a device of the character described, the combination of hand crank operated means for feeding a strip of paper, a cutter guided for rectilinear movement across the path of said strip, mechanism automatically operable to project the cutter across the strip as soon as the feeding means has moved through a predetermined cycle, and means 10 operated by said mechanism to positively lock the feeding means during the entire time that the cutter is operating. 15
3. In a device of the character described, the combination of hand crank operated means for feeding a strip of paper, a cutter movable across the path of said strip, mechanism for advancing the cutter after the feeding means has moved through a predetermined cycle, means controlled by the 20 movement of said mechanism to positively lock the feeding means at the beginning of the movement of the cutter, and to unlock the same only when the cutter has been fully retracted. 25
4. In a device of the character described, the combination of a base, means for feeding a strip of paper thereover, said base having a transverse slot across its face, and a curved slot in rear of the first slot and spaced therefrom, a cutter carriage including a bar with two blades carried thereby and adapted to be projected through the paper and into the respective slots when the bar is advanced, means for positively holding the bar with 30 the blades out of contact with the paper while the feeding means is operating, and means for automatically locking the feeding means after a predetermined cycle of operating and at the same time projecting the cutter. 45
5. In a device of the character described, the combination of a pair of rollers adapted to feed a strip of paper downwardly, a base in front of which the strip passes, said base extending above and below the rollers, guide rods extending forwardly from the base, a cutter carrier slidably mounted on said rods, cutters supported by the carrier in front of said base respectively above and below the 55 rollers, means for locking the rollers and at the same time projecting the cutters through the strip, said base being provided with slots to receive the cutters, and means for retracting the cutters and at the same 60 time releasing the locking means. 65
6. In a device of the character described, the combination of a base, a pair of rollers adapted to feed a strip of paper in front of said base, said base extending above and below the rollers, guide rods extending forwardly from said base, a cutter carrier slidably mounted on said rods, cutters secured to the carrier in front of said base respectively above and below the rollers, means for positively holding the carriage stationary 70 and the cutters out of contact with the paper while the feed rollers are operating, and means for locking the feed rollers after a predetermined cycle of operation and at the same time projecting the cutters through 75 the paper. 80
7. In a device of the character described, the combination of a base, means for feeding a strip of paper thereover, said base having a slot in its face, a cutter adapted to be projected through the paper into the slot, a carriage to which the cutter is secured, guide rods extending forwardly from the base and constituting supports on which the carriage is slidably mounted, a toggle on each end 85 of the carriage connecting the same to the base, means connected with one of the toggles for locking the feeding means when the cutter is projected into the slot, and means for spreading the toggles to retract 90 the cutter and at the same time release said locking means. 95
8. In a device of the character described, the combination of a base, means for feeding a strip of paper in front of the same, said 100 base having a slot in its front face, a cutter adapted to be projected through the paper into the slot, a carriage to which the cutter is secured, guide rods extending forwardly from the base and constituting supports on 105 which the carriage is slidably mounted, springs acting on the carriage to normally maintain the cutter in the slot, a toggle at each end of the carriage connecting the same to the base, means for actuating the 110 toggles to retract the cutter, means carried by one of the toggles and cooperating with the feeding means to positively hold the cutter carriage retracted during a predetermined cycle of the feeding means, and then 115 to release the cutter carriage and lock the feeding means. 120
9. In a device of the character described, the combination of a base having a slot therein, a cutter carriage movable toward 125 and away from the base and having a cutting blade adapted to enter the slot, means for feeding a strip of paper between said carriage and base, and means controlled by the movement of said mechanism for positively locking the feeding means at all times except when the cutter carriage is fully retracted. 125
10. In a device of the character described, the combination of a base, a cutter carriage 130

movable toward and away from the base, hand crank operated means for feeding a strip of paper between said carriage and base, means associated with the feeding means for locking said carriage when the latter reaches the position most remote from the base, and means for releasing the carriage and causing said locking means to lock the feeding means only after the latter has been operated through a predetermined cycle.

11. In a device of the character described, the combination of a feed roller, a drum mounted to rotate simultaneously therewith, a stop pin normally in locking relation to the drum, a reciprocably mounted carriage, means for advancing and retracting said carriage, said means being connected to the stop pin so as to withdraw the latter to release the drum as the carriage completes its retractive movement, and means cooperating with the stop pin to lock the carriage in retracted position until the feed roller and drum are rotated through a predetermined cycle.

12. In a device of the character described, the combination of a feed roller, a drum mounted to rotate simultaneously therewith, a fixed base, a carriage mounted for limited rectilinear movement toward and away from the base, a toggle connecting the carriage to said base, means for advancing the carriage toward the base, means for spreading the toggle to retract the carriage, a stop pin connected to the toggle and normally in locking relation to the drum, being withdrawn from the latter by the toggle only when the carriage is retracted to the limit of its movement, and means cooperating with the stop pin to lock the carriage in retracted position

until the feed roller and drum have completed a predetermined cycle of movement.

13. In a device of the character described, the combination of a drum having a peripheral helical groove with a hole at one end of the groove, a stop pin normally engaging said hole to lock the drum, means for withdrawing said pin to release the drum, means for automatically moving the pin immediately to the other end of the groove as soon as it is withdrawn, means for holding the pin in contact with the bottom of the groove as the drum is rotated, and for again projecting the pin into the hole when it reaches the same.

14. In a device of the character described, the combination of a feed roller, a drum mounted to rotate simultaneously therewith, said drum having a peripheral helical groove with a hole at one end, a stop pin normally engaging said hole to lock the drum, a reciprocably mounted carriage, means for advancing and retracting said carriage, said means being connected to the stop pin so as to withdraw the latter to release the drum as the carriage completes its retractive movement, means for automatically moving the pin immediately to the other end of the groove as soon as it is withdrawn, at the same time locking the carriage in retracted position, means for holding the pin in contact with the bottom of the groove as the drum is rotated, and for again projecting the pin into the hole when it reaches the same, thereby again advancing the carriage.

In testimony, that I claim the foregoing as my own, I have hereto affixed my signature.

ROBERT DILIVAN PARKS.
